UNITED STATES PATENT OFFICE.

WILLIAM B. HAMM, OF PHILADELPHIA, PENNSYLVANIA.

DESIGN FOR A WATCH-CHAIN CHARM.

Specification forming part of Design No. 6,759, dated July 8, 1873; application filed May 28, 1873.

To all whom it may concern:

Be it known that I, WILLIAM B. HAMM, of the city of Philadelphia and State of Pennsylvania, have invented a Design for a Personal Ornament, to be worn and known by the name of "a Charm," of which the following is a specification:

The nature of my design is fully represented in the accompanying drawing, and is described as follows: A fac-simile of the original bell of Independence Hall, at Philadelphia, State of Pennsylvania, known as the "Old Liberty Bell of 1776."

I claim as my invention—

The design for a charm for attachment to watch-chains, &c., substantially as herein shown and described.

WILLIAM B. HAMM.
